SALIVA EJECTOR AND REFLECTOR

Henry Friedman, Chicago, Ill.

Application February 21, 1947, Serial No. 729,953

4 Claims. (Cl. 32—33)

1

This invention relates to improvements in a saliva drain or ejector of the type commonly placed in a patient's mouth during a dental operation.

The heretofore used type of saliva ejectors usually comprised a bent tube, one end of which was placed in the patient's mouth, the other end being connected to a vacuum system contained in the dental unit. The open end of the tube, which was placed in the patient's mouth, usually drew into the mouth of the tube a part of the soft tissue contained in the mouth and caused extreme discomfort and, further, completely or partially blocked the tube opening and consequently preventing entirely, or greatly impeding, the passage of saliva through the tube. The heretofore used ejectors were a one-purpose instrument and offered no aid to the dental operation except to remove the saliva from the patient's mouth. It was to overcome these and other inherent defects that the present invention was conceived.

The main objects of this invention are to provide a saliva ejector which will prevent the soft tissue in the mouth from being drawn into the instrument when placed in a patient's mouth during use; to provide a device of this character which will act as a reflector; to provide a device of this character which will also function as a tongue retractor; to provide a device of this character having a highly polished front and back surface, both of which will act equally well as a mirror or reflector; to provide a device of this character having a baffle plate in front of the saliva intake apertures; to provide a device of this character having the saliva intake end thereof offset from the handle portion; to provide a device of this character having no exposed sharp or rough edges; to provide a device of this character which can be easily and readily sterilized; and to provide a device of this character which is relatively simple in construction and inexpensive to manufacture.

A specific embodiment of this invention is shown in the accompanying drawings in which:

Figure 1 is a perspective view of my invention.

Fig. 2 is an elevational view taken on line 2—2 of Fig. 1 showing a portion thereof broken away and in cross section.

Fig. 3 is an enlarged perspective view of the saliva intake and mirrored end of the device.

Fig. 4 is an edge view of the device.

Fig. 5 is a cross-sectional view taken on line 5—5 of Fig. 1.

Fig. 6 is a cross-sectional view taken on line 6—6 of Fig. 1.

2

Fig. 7 is an enlarged edge view of the head, part of the drain tube being shown broken away.

Referring in detail to the drawings, the improved saliva ejector comprises a metal tube, bent substantially in L-shape having a relatively long leg 1 and a laterally extending shorter leg 2. A metal handle or hand grip member 3, almost completely enveloping the leg 1, is square shaped in cross section and tapered toward the leg 2 and integrally secured to the leg 1 intermediate the ends thereof in any suitable manner, such as by welding, soldering or the like. Scored depressions or finger grips 7 and 8 are positioned on either side of the forward end of the body 3 adjacent the collar 6. The free end of the short leg 2 is provided with a diagonal face as indicated generally by the numeral 9 and clearly illustrated in Figs. 4 and 7.

The drain or saliva-receiving head is formed 20 from a piece of metal tubing 10 and is of the same diameter as the leg 2. The tube 10 is preferably bent in oval form and has the free ends thereof joined to form a continuous passage. The tube 10 is provided with an elongated aperture 25 11, positioned on one side thereof. The free end of tube leg 2 is secured to the margin of the aperture 11 in any suitable manner, such as by welding, soldering or the like, whereby a continuous passage is formed between the oval shaped tube 10 and the tubular legs 1 and 2. It will be apparent that the tube 10, when secured to the end 9 of leg 2, will be offset in a diagonal plane from the longitudinal plane of the leg 2 and will depend therefrom.

35 A plurality of diagonally positioned ports 12 are positioned in the tube 10 and in the portion directly opposite to the portion at which the leg 2 is attached thereto, as clearly illustrated in Fig. 6. A baffle plate 13, preferably formed of a non-corroding metal, having a plurality of apertures, or perforations 14 therein, is rigidly secured to the face of the drain tube 10 in any suitable manner, such as by welding, or the like, and covers a portion thereof. As illustrated, the baffle plate is positioned on the tube 10 adjacent the point containing the ports 12.

40 A thin flat disc or wafer 15, preferably formed of a non-corroding metal and highly polished on both surfaces to form a double mirror or reflector, is rigidly secured within the inner area of the oval-shaped tube 10 and thereto, in any suitable manner such as by welding or brazing or the like.

45 In the operation, the free end of the leg 1 is attached to the drain tube of the vacuum sys-

tem, which is a part of all standard dental units, in the conventional manner. The oval-shaped tube 10 is placed in the patient's mouth so that the body thereof lies under and retracts the patient's tongue and between and below the lower gums of the patient. Accumulated saliva in this pocket will flow over the top of the baffle plate 13 and/or through the perforations 14 and into the ports 12, whereby it will be drawn out of the mouth by the vacuum system through the legs 1 and 2 and tube 10 and disposed of in the usual manner. It will be understood that the leg 2 rests on the lower teeth of the patient and the leg 1 depends therefrom in substantially a vertical plane, as is usual with all types of saliva ejectors.

It will be apparent that since the suction action takes place at the ports 12 and these ports are completely housed behind the baffle plate 13, the soft tissues in the mouth cannot be drawn into the ports 12. It will also be seen that all saliva passing over the top edge of the baffle plate 13 or through the perforations 14 will accumulate in the pocket formed by the tube 10, the face of the disc 15 and the rear face of the baffle plate 13 whereby it will readily be drawn into the ports 12.

The polished disc 15 may be used as a conventional dental mirror or may be used as a reflector to concentrate more light in the patient's mouth, as will be apparent.

It is to be understood that all joints connecting the various parts of the device together are all perfectly smooth so that there will be no danger of cutting or tearing the mouth or lips and it is preferred that the entire device be coated with a rust-resisting polished material such as chrome plate or the like, whereby washing and sterilization of the instrument may be facilitated.

Although but one specific embodiment has been shown and described, it is to be understood that details may be altered or omitted without departing from the spirit of this invention, as defined by the following claims.

I claim:

1. A device of the character described comprising a relatively long tube; a relatively short tube integrally secured to one end of said long tube extending laterally therefrom and communicating with the interior thereof; an oval-shaped tube secured to the free end of said short tube, said tubes having a continuous uninterrupted passage therethrough, said oval-shaped tube having a plurality of ports located diametrically opposite the point of attachment of said short tube to said oval-shaped tube; a polished disc rigidly secured medially to the inner marginal edge of said oval-shaped tube; a flat baffle plate having a plurality

of spaced perforations therein rigidly secured to the face of said oval-shaped tube and extending thereacross at a point immediately adjacent said ports.

5 2. A device of the character described comprising a relatively long tube, a laterally extending short tube communicating with and attached at one end to said long tube, a third tube bent in oval-shape and having a plurality of ports therein, the free end of said short tube being rigidly secured to said oval tube at a point diametrically opposite said ports, all of said tubes having a common passageway therethrough communicating with each other, a polished disc, the marginal edges thereof rigidly secured to the inner peripheral edges of said oval-shaped tube; a baffle plate integrally secured to and across a portion of said oval tube adjacent to and in front of said ports, and a hollow tapered handle integrally secured to said long tube intermediate of the ends thereof.

20 3. A device of the character described comprising a hollow handle having an outlet port therein, a laterally extending tube, one end thereof being integrally secured to the end of said handle opposite said outlet port and having communication therewith, reflecting means rigidly secured to the free end of said tube; hollow means on said reflecting means having communication with said tube whereby a continuous passage is formed to said outlet port, a drain port in said hollow means, and a baffle plate secured in front of said drain port and to said hollow means.

25 4. A device of the character described comprising in combination with a retractor means, a reflector, and a saliva-carrying means combined in a unitary structure; a hollow handle secured to said saliva-carrying means, a passageway in said saliva-carrying means communicating with the interior of said handle, said handle having an outlet in one end thereof, a drain port in said saliva-carrying means, and a baffle plate in front of said port and secured to said saliva-carrying means, said baffle plate lying partially across said reflector.

HENRY FRIEDMAN.
